UNITED STATES PATENT OFFICE.

KARL LIEBENOW, OF LÜBECK, GERMANY, ASSIGNOR TO RICHARD STEIN AND EDUARD AHRENKIEL, BOTH OF LÜBECK, GERMANY.

HAIR-BUCKLE.

1,373,088.

Specification of Letters Patent. Patented Mar. 29, 1921.

Application filed August 4, 1920. Serial No. 401,264.

To all whom it may concern:

Be it known that I, KARL LIEBENOW, citizen of Germany, residing at Lübeck, Germany, have invented certain new and useful 5 Improvements in Hair-Buckles, of which the following is a specification, reference being had therein to the accompanying drawing.

The invention is a hair-buckle especially 10 for fastening of ribbon loops to a braid of hair, which is done by pushing the squeezed-together hair V-shaped through the buckle. According to the invention a tongue fastened on the frame of the buckle and squeezing 15 the hair into the buckle, is by means of a striker, fastened on the closing plate, pressed into closing position and held tight.

On the drawing the new hair buckle is 20 shown in example as follows:

Figures 1 and 2 show the buckle in side view opened and closed.

Fig. 3 is a front view.

Fig. 4 is a perpendicular cross-cut, and

Fig. 5 is an upper-view with opened plate.

To the cross beam of the buckle frame *a*, 25 consisting of wire, on one side the squeezing tongue *b*, on the other side the closing plate *c* is turnably fastened. The tongue *b* is lying in length middle of the frame *a* and can be freely moved through the same. The plate *c*, which can be stiffened by long-ribs *c*¹ contains an under striker *d*, the front 30 springing part *e* of the tongue being angular and bent in hook-form, so that this part catches over the joint box of the tongue *b*.

For use the ready tied ribbon loops are fastened to a long beam of the frame *a*. Hereafter the hair is put on the frame *a* 40 of the opened buckle and the tongue *b*

pushed into the hair and the frame. Now the plate *c* is brought in closing position, whereby the striker *d* hits on the front part of the tongue *b* and holds the same tight, whereon the hook-formed part *e* catches 45 over the joint box *f*, so that the buckle is closed. The hair now lies in the known manner V-formed pressed in the buckle, whereby this position is once held by the long beam of the frame *a* and on the other 50 side by the tongue (Fig. 4).

The buckle is totally covered by the loop *g* hanging over the same.

By opening the plate *c* the buckle can be taken off the hair easily.

55

What I claim is:

1. A hair buckle designed for fastening loops of material to a braid of hair, comprising a buckle frame with a pivoted tongue, a striker, and a closing plate pivotally mounted and carrying said striker, whereby the hair is pushed through the buckle in substantially V-form. 60

2. A hair buckle designed for fastening loops of material to a braid of hair, comprising a buckle frame with a pivoted tongue, a striker, and a closing plate pivotally mounted and carrying said striker, whereby the hair is pushed through the buckle in substantially V-form, the said 65 striker being an end extension of the closing plate and the striker adapted to engage the tongue when the plate is forced to its closed position.

In testimony whereof I affix my signature 70 in the presence of two witnesses.

KARL LIEBENOW.
